COMBINED GLASS RETAINER AND SPOON HOLDER

Alice A. Ellison, 13600 Bracken St.,
Arleta, Calif. 91331

Filed July 29, 1968, Ser. No. 12,953

Term of patent 14 years

Int. Cl. D7—01, 99

U.S. Cl. D44—10

FIG. 1.

FIG. 2.

FIG. 3.

FIG. 4.

FIG. 5.

FIG. 1 is a top plan view of a combined glass retainer and spoon holder showing my new design;

FIG. 2 is a side elevation thereof looking in the direction of arrow 2 of FIG. 1;

FIG. 3 is a bottom plan view thereof;

FIG. 4 is a top perspective view thereof; and,

FIG. 5 is a bottom perspective view thereof.

I claim:

The ornamental design for a combined glass retainer and spoon holder, substantially as shown.
